Inventor

John A. E. Anderson.

UNITED STATES PATENT OFFICE.

JOHN A. E. ANDERSON, OF LEBANON, ASSIGNOR TO HIMSELF AND JACOB GUSHWA, LAFAYETTE, INDIANA.

LOCK AND LATCH COMBINED.

SPECIFICATION forming part of Letters Patent No. 331,671, dated December 1, 1885.

Application filed March 13, 1884. Serial No. 124,122. (No model.)

To all whom it may concern:

Be it known that I, JOHN A. E. ANDERSON, a citizen of the United States, residing at Lebanon, in the county of Boone and State of Indiana, have invented a new and useful Lock and Latch Combined, of which the following is a specification.

My invention relates to improvements in weight-lever latch-locks, the objects being to cheapen and simplify the latch operating and locking mechanism. I attain these objects by the mechanism illustrated in the accompanying drawings, in which—

Figure 1 is a side view of the lock with one plate removed to show the form, construction, and arrangement of the several parts; and Fig. 2 is a transverse vertical section on line *xx*, Fig. 1.

Similar letters refer to the same parts throughout the several figures.

A is the case containing the working parts of the lock.

B is the weighted latch-lever, having its fulcrum at *b*, the greatest practicable distance from its center of gravity.

H, the latch or bolt, is attached at *h* so as to be reversible, thereby adapting it to either side of a door.

C is the knob-lever, having its bearings in the side plates of the case. The knob-shaft I passes through the lever C, and the lever is formed and arranged, as shown, so as to engage with both the arm B' of weight-lever B and one arm of the intermediate lever, D, having its fulcrum at *d*. It is obvious that from this arrangement a right or left turn of knob-shaft I will raise weight-lever B, and thus operate the latch H.

E is a segmental locking-tumbler, having a downward V-shaped projection, *e*. This tumbler rests loosely on an annular slotted guide, F, the V-shaped projection passing through the slot so that the key may engage with it, and whereby it is reciprocated about the guide F.

To provide for release of the key when the tumbler has been rotated to either the locked or unlocked position, the under side of weight-lever B is formed so that space is provided for the tumbler to be raised from its seat by pressure of the key against the inclined sides of V-shaped projection *e*, thus allowing the key to pass under it.

G is a segmental annular guard arranged within rest F, to prevent other instruments than the proper key being used to manipulate tumbler E. *f f* are rests for tumbler E. A spring, *i*, may be employed, if desired, to hold the weight-lever B more firmly in position.

The form given to the single weight-lever B, with its arm B', together with the position of its fulcrum at *b*, is such as to secure the greatest practicable weight consistent with its required movement between the mechanism for operating it and the locking device, and at the same time to provide for placing the knob-shaft and key-hole in the same vertical plane at the greatest practicable distance apart and at the greatest practicable distance from the door-jamb, so that convenient access may be had to them.

The upperside of segmental locking-tumbler E is formed with recesses near its ends to receive the downward projection *e* of weight-lever B, which holds it from being easily moved out of position, except as manipulated by the key.

What I claim is—

In a weight-lever lock-latch, the combination of a single weight-lever, B, formed, as shown, with arm B', and projection *e*, knob-lever C, intermediate lever, D, and segmental locking-tumbler E, having recesses in its periphery, substantially as set forth.

JOHN A. E. ANDERSON.
